Primary Examiner—C. A. Murphy*Attorney, Agent, or Firm*—Daniel C. McKown[57] **CLAIM**

The ornamental design for cycling shorts, as shown and described.

DESCRIPTION

FIG. 1 is a front elevational view of cycling shorts showing my new design, the broken lines shown on the claimed article throughout the views being understood to represent conventional stitching;

FIG. 2 is a rear elevational view thereof;

FIG. 3 is a left side elevational view thereof, the right side being a mirror image;

FIG. 4 is a top plan view thereof;

FIG. 5 is a bottom plan view thereof; and,

FIG. 6 is a left front bottom perspective view thereof, the broken lines partially showing a human body being for illustrative purposes only and forming no part of the claimed design.
